ROBERT M. CRAIG, OF WILKINSBURG, PENNSYLVANIA.

PROCESS OF MAKING METALLIC DENTURE-BACKINGS.

1,353,565.

Specification of Letters Patent. Patented Sept. 21, 1920.

Application filed June 19, 1919. Serial No. 305,421.

To all whom it may concern:

Be it known that I, ROBERT MEADE CRAIG, a citizen of the United States, residing at Wilkinsburg, in the county of Allegheny 5 and State of Pennsylvania, have invented a certain new and useful Improvement in Processes of Making Metallic Denture-Backings, whereof the following is a specification, reference being had to the accompanying drawing.

My improvement relates to the manufacture of metallic backings for porcelain tooth facings of the class contemplated in Letters Patent 12,753 reissued to me February 18, 15 1908, which may be utilized in a plate, bridge, or other form of denture.

In Letters Patent of the United States 1,221,420, granted to me April 3, 1917, I described a process of making such a backing 20 by apposing oppositely counterpart cast metal members, spaced and arranged to embrace the porcelain body between them and then uniting said metallic members by a fusible element between them. Such construction is advantageous in that such members of a single size may be used to form metallic backings of different sizes, by interposing more or less of the fusible element 25 between them. However, that method of manufacture requires a great deal of time and skilled labor, and it is the object of my present invention to provide a method of quantity production of backings each formed of a single piece of pressed sheet metal, with 30 the minimum amount of labor, by means of dies. Said single piece backing, and such die means, form the subject matter of other applications for Letters Patent of the United States copending herewith and respectively 35 40 Serial Number 307,104, filed June 27, 1919, and Serial Number 308,590, filed July 3, 1919.

In accordance with my improved process, a primarily plane strip of sheet gold, or 45 other suitable metal or alloy, of uniform thickness, is drawn through suitable dies to form a bar, having opposite concave faces of substantially cylindriform curvature, so that the opposite longitudinal edges of said 50 bar are about twice as thick as the middle portion thereof, throughout its length. Said bar is then divided to form a plurality of backing blanks, by similar successive punching operations, each of which produces a 55 single blank of approximately rhombic configuration, the shorter axis of which coin-

cides with the longitudinal axis of said bar. Each of said blanks is then pressed, in suitable dies, so as to turn its thick edges upward, in substantially parallel relation, so 60 that it is U-shaped in cross section, considered transversely with respect to the original bar. Such pressing operation contemporaneously arches said blank at its intermediate portion so that the exterior of 65 the bight of the U is concavely curved in the direction of the length of said bar, in conformity with the posterior portion of the porcelain body which is to be embraced between the bifurcations of said backing. 70

My improved process produces a backing which differs from that shown in my Letters Patent 1,221,420 not only in that it is formed of a single piece of sheet metal, instead of being formed of two pieces of 75 cast metal, which must be fused in connection with an intermediate piece; but also in that the web thereof intermediate of its side flanges is of uniform cross section throughout its length, and thinner at its 80 medial longitudinal axis than at its opposite edges. Therefore, my improved process effects a material saving in gold, in comparison with that described in said Letters Patent 1,221,420; because the intermediate 85 web of the three piece backing shown in the latter was not only of irregular cross section throughout its length but of considerable thickness to insure the effective engagement of the fusible element. 90

Consequently, my improved process is advantageous, as compared with that disclosed in said Letters Patent, not only in that it produces a metallic backing of the specific class contemplated at great saving of skilled 95 labor and consequent cost of manufacture; but with a substantial saving in the amount of precious metal required for a given backing.

My invention includes the various novel 100 features of procedure herein specified and claimed.

In said drawing; Figure I is a perspective view of a portion of a bar, produced from a primarily plane strip of sheet metal of 105 uniform thickness, conveniently by a drawing operation.

Fig. II is a perspective view of a single backing blank punched from said bar.

Fig. III is a perspective view of a U- 110 shaped backing pressed from said blank; the curved dash and dot line therein being

in the plane of the longitudinal axis of the bar indicated by the dash and dot line in Fig. I, and indicating the extent to which the web intermediate of the bifurcations of 5 said backing has been bent from its primarily straight form.

Fig. IV is a central longitudinal sectional view of said backing; the plane of section coinciding with the longitudinal axis of 10 said bar indicated by the dash and dot line in Fig. I.

Fig. V is a plan view of said backing member in a denture representing a bicuspid tooth, showing that the apposed flanges 15 formed by the bifurcations of the U-shaped backing are closer together at their free edges than at their junction with said web, so as to form an undercut recess to receive and retain the porcelain tooth body of said 20 denture.

Fig. VI is a front elevation of said denture.

Fig. VII is a left side elevation of said denture.

Fig. VIII is a rear elevation of said 25 denture.

Referring to Fig. I; the bar aforesaid has its opposite faces concavely and substantially cylindriformly curved throughout its 30 length, so as to form a thin web 1 with opposite thick longitudinal edges 2, of the same transverse cross section, throughout its length. Such a bar is preferably formed by drawing a primarily plane and uniformly 35 thick strip of sheet metal, between apposed die members; while said bar is progressed in the direction of its length. However, it is to be understood that such a bar as shown in Fig. I may be otherwise produced, for 40 instance, by a drop forging, or swaging, operation. Therefore, although I include the operation of drawing said bar as a step in one of the appended claims for my invention; I omit it from other claims, in 45 which the preformation of such a bar, by any suitable method or means, is assumed.

The dotted lines shown in Fig. I indicate the outlines of respective backing blanks 3, which may be successively formed from said 50 bar by punching operations. It may be observed that such outlines are of slightly greater extent, transversely with respect to said bar, than the width of the bar. That effect is attained by such construction and 55 arrangement of the punching dies that they not only cut each blank from said bar, but contemporaneously swage it, so as to slightly reduce the thickness of the edges of said bar. Such swaging operation not only 60 spreads the blank 3 but makes the metal thereof more compact, so as to increase its stiffness to the degree which is desirable for the performance of its function of retaining a porcelain body. In other words it is to be 65 understood that it is preferable to employ

metal in a state of maximum ductility to form the bar shown in Fig. I, because such condition of the metal facilitates whatever operation is employed to reduce the primarily plane sheet metal to the concave bar form, and it is also desirable to have the metal in a ductile state to facilitate the punching operation by which the blanks are formed. However, it is desirable to have the metal in the finished backing in a less ductile 70 state and, therefore, it is advantageous to so conduct the operations of producing said blank that the product has the desired degree of stiffness to perform its function, and I prefer to attain said result by combining a swaging operation with the operation of punching said blanks as described. However, as all of the metals and alloys which are desirable to employ in making such 75 backings are of the character in which the degree of rigidity thereof is directly related to the density thereof, attainable by compressing the metal; it is obvious that the desired degree of density of the metal may be attained before the punching operation. 80 Therefore, although I include the step of swaging the metal contemporaneously with the operation of punching it, in an appended claim, I do not desire to limit all of my 85 claims to that specific step.

Referring to Fig. II; it may be observed that the backing blank 3 is of approximately rhombic outline, having its axis 4 corresponding with the longitudinal axis of said bar; so that the major portion of its area 90 is formed of the thinner portions of said bar, only a fraction of said area being formed of the thickest, edge portions, of said bar.

Referring to Fig. III; it may be observed that the substantially U-shaped metallic 105 backing, formed from said blank 3, has opposite side flanges formed by the thick edges 2 aforesaid, bent so that they converge both from the bottom toward the top and from the intermediate web 1 toward the 110 observer. Although said side flanges merge into said web directly at the upper edge of the latter; they merge into said web above the lower edge of the latter so as to leave a downwardly projecting portion 5, which, as 115 hereinafter described, forms a locking flange for engagement with the porcelain facing to prevent the accidental escape of the latter from said backing. As it is intended that said flange 5 may be returned to the position shown in Figs. III and IV to 120 permit said facing to be removed at any time; the metal of the blank thereat must be left in such ductile condition as to permit repeated flexure, without fracturing it. 125 That result is attained by confining the swaging operation aforesaid to the flanged portions of said blank. In other words; my invention as defined in the most specific 130 claim appended hereto has the advantage of

producing a backing in which the metal is of different degrees of ductility at different regions thereof, in accordance with the particular stresses to which those regions are intended to be subjected.

Referring to Figs. V to VIII inclusive; the porcelain body, which forms the facing for the metallic backing aforesaid, comprises the anterior portion 7 and the posterior portion 8 in unitary relation. Said anterior portion may be of any desired size, representing a natural tooth, and said posterior portion forms a dovetail 9 whereby said body is supported in and engaged by said metallic backing 10, which may form part 10 of a plate, bridge, or other denture, to which it may be joined by a soldering or other suitable operation.

As indicated by the dotted lines in Figs. 20 V, VI and VIII; said dovetail 9 is wedge shaped in two directions at right angles to each other, its side faces converging both from its occlusal end 11 to its gingival end 12 and from its lingual side 13 to its 25 labial or buccal side 14, where it merges into the anterior portion 7 of said body; said converging faces being symmetrically disposed with respect to the central vertical plane of said porcelain body. Said posterior dovetail portion 9 is also converged and concavely curved longitudinally in its lingual face, from its gingival end toward its occlusal end, as best shown at 9 in Fig. VII. Said posterior portion 8 of said porcelain 30 body being thus converged in three directions, as above described, is fitted in the correspondingly shaped recess in said metallic backing 10, the exterior contour 14 of which resembles that of the tooth imitated by the 35 anterior portion 7 of said porcelain body.

The construction and arrangement above described are such that the strains to which the denture is normally subjected viz., pressure in a direction from its occlusal or incisal end toward its gingival end, and transversely from its lingual side to its labial side, merely serve to more firmly seat said porcelain body in its backing 10. Although there is no normal strain upon said denture tending 40 to remove said porcelain body from its metallic backing in a direction from its gingival end to its occlusal end, it may be manually slid and removed in that direction, without removing the backing from its 45 setting, whenever it is desired to remove the porcelain body. Therefore, although it is unnecessary to provide any special means for preventing such sliding movement in addition to the frictional engagement between said porcelain body and its backing, I 50 prefer to provide said backing 10 with the unitary locking flange 5 which, when bent as indicated in dotted lines in Fig. IV, and in full and dotted lines in Fig. VII, normally 55 prevents said porcelain body from

thus sliding; so that it is necessary to straighten said flange 5 to the position shown in full lines in Fig. IV and in dotted lines in Fig. VII to remove said body. Therefore, said locking flange 5 may be repeatedly flexed to engage and disengage a porcelain body in said backing 10. 70

My present process also differs from that described in said Letters Patent 1,221,420 in that it is necessary to have dies of respectively different sizes corresponding with different sizes of natural teeth, to form the blanks shown in Fig. II and bend them as exemplified in Fig. III. However, the cost of such dies is negligible as compared with 80 the great saving in cost of manufacture above contemplated. Moreover, a single bar, such as shown in Fig. I, may be of such size and proportions that it may be used for all sizes of blanks required, and all sizes of 85 porcelain bodies for a given tooth may be conveniently recessed alike, to receive the side flanges of metallic backings 10 as above described, so that the dies for forming the different sizes of the latter may all be of one 90 pattern, for a given tooth, except that they are of respectively different widths.

Therefore, I do not desire to limit myself to the precise details of construction and arrangement herein set forth, as it is obvious 95 that various modifications may be made therein without departing from the essential features of my invention, as defined in the appended claims.

1. In a process of making a metallic denture backing adapted to hold a nonmetallic tooth body; drawing a strip of primarily plane and uniformly thick sheet metal to form a bar having opposite concave faces of substantially cylindriform curvature, so that 100 the opposite longitudinal edges of said bar are thicker than the middle portion thereof, throughout its length; forming a blank of approximately rhombic configuration, by punching the same from said bar, with the 105 shorter axis of said blank coinciding with the longitudinal axis of said bar, and simultaneously swaging said blank to increase its dimensions transversely with respect to said bar; thereby rendering the middle of 110 said blank less ductile at the regions swaged than at the regions which are merely punched; pressing said blank so as to arch the thinner portion thereof in the direction of the axis of said bar, and bend the 115 thicker portions thereof transversely with respect to said thinner portion thereof, to form a backing which is U-shaped in cross section, considered transversely with respect to said bar, the bifurcations thereof forming 120 opposite side flanges which merge into the intermediate web directly at one end of the latter but terminate short of the opposite end of said web, leaving the latter projecting to form a locking flange; whereby 125 130

the exterior of the bight of the U of said backing is concavely curved in the direction of the length of said bar, in conformity with the posterior portion of said nonmetallic 5 body which is to be embraced between the bifurcations of said backing, and said bifurcations form a recess which is wedge shaped in three directions, to wit, in respectively opposite directions longitudinally 10 with respect to said arched portion thereof and in one direction transversely to said web, the web between said side flanges being wider at the end provided with said locking flange than at the other end, the 15 space between the bifurcations of said backing being wider at its bight than at the free ends of said bifurcations, and the space between said bifurcations being wider at the end of said backing opposite said locking 20 flange than intermediate of the length of said backing with respect to the axis of said bar.

2. In a process of making a metallic denture backing adapted to hold a nonmetallic 25 tooth body; drawing a strip of primarily plane and uniformly thick sheet metal to form a bar having opposite concave faces, and opposite longitudinal edges thicker than the middle portion thereof; forming a 30 blank by punching the same from said bar, and simultaneously swaging said blank to increase its dimensions transversely with respect to said bar; thereby rendering the metal of said blank less ductile at the 35 regions swaged than at the regions which are merely punched; pressing said blank so as to bend the thicker portions thereof transversely with respect to said thinner portion thereof, to form a backing which is U- 40 shaped in cross section, considered transversely with respect to said bar, the bifurcations thereof forming opposite side flanges which merge into the intermediate web directly at one end of the latter but terminate 45 short of the opposite end of said web, leaving the latter projecting to form a locking flange; whereby said bifurcations form a recess which is wedge shaped in three directions, to wit, in respectively opposite directions longitudinally with respect to said 50 arched portion thereof and in one direction transversely to said web, the web between said side flanges being wider at the end provided with said locking flange than at the other end, the space between the bifurcations of said backing being wider at its 55 bight than at the free ends of said bifurcations, and the space between said bifurcations being wider at the end of said backing opposite said locking flange than intermediate of the length of said backing with respect to the axis of said bar.

3. In a process of making a metallic denture backing adapted to hold a nonmetallic 65 tooth body; drawing a strip of primarily

plane and uniformly thick sheet metal to form a bar having opposite concave faces, and opposite longitudinal edges thicker than the middle portion thereof; forming a blank by punching the same from said bar; 70 pressing said blank so as to bend the thicker portions thereof transversely with respect to said thinner portion thereof, to form a backing which is U-shaped in cross section, considered transversely with respect to said bar, the bifurcations thereof forming opposite side flanges which merge into the intermediate web directly at one end of the latter but terminate short of the opposite end of said web, leaving the latter projecting to 75 form a locking flange; whereby said bifurcations form a recess which is wedge shaped in three directions, to wit, in respectively opposite directions longitudinally with respect to said arched portion thereof and in one direction transversely to said web, the web between said side flanges being wider at the end provided with said locking flange than at the other end, the space between the bifurcations of said backing being wider at its bight than at the free ends of said bifurcations, and the space between said bifurcations being wider at the end of said backing opposite said locking flange than intermediate of the length of said backing with 85 respect to the axis of said bar.

4. In a process of making a metallic denture backing adapted to hold a nonmetallic tooth body; working a strip of primarily plane and uniformly thick sheet metal to 90 form a bar with opposite longitudinal edges thicker than the middle portion thereof; forming a blank by punching the same from said bar, and simultaneously swaging said blank to increase its dimensions transversely with respect to said bar; thereby rendering the metal of said blank less ductile at the 95 regions swaged than at the regions which are merely punched; pressing said blank so as to arch the thinner portion thereof in the direction of the axis of said bar, and bend the thicker portions thereof transversely with respect to said thinner portion thereof, to form a backing which is U-shaped in cross section, considered transversely with respect to said bar, the bifurcations thereof forming opposite side flanges which merge into the intermediate web directly at one end of the latter but terminate short of the opposite 100 end of said web, leaving the latter projecting to form a locking flange; whereby the exterior of the bight of the U of said backing is concavely curved in the direction of the length of said bar, in conformity with the posterior portion of said nonmetallic 105 body which is to be embraced between the bifurcations of said backing, and said bifurcations form a recess which is wedge shaped, the web between said side flanges being wider at one end than at the other end, and 110

120

125

130

the space between the bifurcations of said backing being wider at its bight than at the free ends of said bifurcations.

flanges; whereby the exterior of the bight of the U of said backing is concavely curved in the direction of the length of said bar, in conformity with the posterior portion of said nonmetallic body which is to be embraced between the bifurcations of said backing, and said bifurcations form a recess which is wedge shaped in three directions, to wit, in respectively opposite directions longitudinally with respect to said arched portion thereof and in one direction transversely to said web, the web between said side flanges being wider at the end provided with said locking flange than at the other end, the space between the bifurcations of said backing being wider at its bight than at the free ends of said bifurcations and the space between said bifurcations being wider at the end of said backing opposite said locking flange than intermediate of the length of said backing with respect to the axis of said bar.

9. In a process of making a metallic denture backing adapted to hold a nonmetallic tooth body; punching a bar having opposite longitudinal edges thicker than the middle portion thereof, to form a blank of approximately rhombic configuration, with the shorter axis of said blank coinciding 25 with the longitudinal axis of said bar; pressing said blank so as to arch the thinner portion thereof in the direction of the axis of said bar, and bend the thicker portions thereof transversely with respect to said 30 thinner portion thereof, to form a backing which is U-shaped in cross section, considered transversely with respect to said bar, the bifurcations thereof forming opposite side flanges; whereby the exterior of the 35 bight of the U of said backing is concavely curved in the direction of the length of said bar, in conformity with the posterior portion of said nonmetallic body which is to be embraced between the bifurcations of said 40 backing, and said bifurcations form a recess which is wedge shaped in three directions, to wit, in respectively opposite directions longitudinally with respect to said arched portion thereof and in one direction 45 transversely to said web, the web between said side flanges being wider at the end provided with said locking flange than at the other end, the space between the bifurcations 50 of said backing being wider at its bight than at the free ends of said bifurcations, and the space between said bifurcations being wider at the end of said backing opposite said locking flange than intermediate 55 of the length of said backing with respect 60 to the axis of said bar.

10. In a process of making a metallic denture backing adapted to hold a nonmetallic tooth body; forming a blank of approximately rhombic configuration, by punching 65 the same from a bar, with the shorter axis

of said blank coinciding with the longitudinal axis of said bar; pressing said blank so as to arch the thinner portion thereof in the direction of the axis of said bar, and bend the thicker portions thereof transversely with respect to said thinner portion thereof, to form a backing which is U-shaped in cross section, considered transversely with respect to said bar; the bifurcations thereof forming opposite side flanges 70 with an intermediate recess which is wedge shaped in three directions, to wit, in two opposite directions longitudinally with respect to said bar axis and in one direction transversely to said axis; the web between 75 said side flanges being wider at one end than at the other end, and said recess between said bifurcations being wider at their bight than at the free ends of said bifurcations. 80 85

11. In a process of making a metallic denture backing adapted to hold a nonmetallic tooth body; forming a blank by punching the same from a bar; pressing said blank so as to arch the thinner portion thereof in the direction of the axis of said bar, and bend the thicker portions thereof transversely with respect to said thinner portion thereof, to form a backing which is U-shaped in cross section, considered transversely with respect to said bar; the bifurcations thereof forming opposite side flanges with an intermediate recess which is wedge shaped in three directions, to wit, in two opposite directions longitudinally with respect to said bar axis and in one direction transversely to said axis; the web between said side flanges being wider at one end than at the other end, and said recess between said bifurcations being wider at their bight than at the free ends of said bifurcations.

12. In a process of making a metallic denture backing adapted to hold a nonmetallic tooth body; forming a bar having opposite concave faces of substantially cylindriform curvature, with opposite longitudinal edges thicker than the middle portion thereof, throughout its length; forming a blank by punching the same from said bar; pressing 110 said blank so as to arch the thinner portion thereof in the direction of the axis of said bar, and bend the thicker portions thereof transversely with respect to the thinner portion thereof, to form a backing 115 which is U-shaped in cross section, considered transversely with respect to said bar, the bifurcations thereof forming opposite side flanges for retaining said tooth body. 120

13. In a process of making a metallic denture backing adapted to hold a nonmetallic tooth body; forming a bar having opposite concave faces of substantially cylindriform curvature, with opposite longitudinal edges thicker than the middle portion thereof, 130

- throughout its length; forming a blank by punching the same from said bar; pressing said blank so as to bend the thicker portions thereof transversely with respect to 5 the thinner portion thereof, to form a backing which is U-shaped in cross section, considered transversely with respect to said bar, the bifurcations thereof forming opposite side flanges for retaining said tooth body.
- 10 14. In a process of making a metallic denture backing adapted to hold a nonmetallic tooth body; forming a blank by punching the same from a concave bar; pressing said blank so as to arch the thinner portion there- 15 of in the direction of the axis of said bar, and bend the thicker portions thereof transversely with respect to the thinner portion thereof, to form a backing which is U-shaped in cross section, considered trans- 20 versely with respect to said bar, the bifurcations thereof forming opposite side flanges for retaining said tooth body.
15. In a process of making a metallic denture backing adapted to hold a nonmetallic tooth body; forming a blank by punching the same from a concave bar; pressing said blank so as to bend the thicker portions 25

thereof transversely with respect to the thinner portion thereof, to form a backing which is U-shaped in cross section, consid- 30 ered transversely with respect to said bar, the bifurcations thereof forming opposite side flanges for retaining said tooth body.

16. In a process of making a metallic denture structure; punching a concave bar to 35 form a blank; rendering the thicker portions of said blank less ductile than the thinnest portion thereof, by swaging them; and bending said thicker portions transversely to said thinnest portion, to form a 40 recess between them.

17. In a process of making a metallic denture structure; punching a concave bar to form a blank; and bending the thicker portions of said bar transversely to its thinnest 45 portion, to form a recess between them.

In testimony whereof, I have hereunto signed my name at Wilkinsburg, Pennsylvania, this sixth day of November, 1918.

ROBERT M. CRAIG.
